Attorney

UNITED STATES PATENT OFFICE.

GEORGE A. SMITH, OF BALTIMORE, MARYLAND.

CLOTHES-HANGER.

1,260,083.

Specification of Letters Patent. Patented Mar. 19, 1918.

Application filed September 29, 1916. Serial No. 122,886.

To all whom it may concern:

Be it known that I, GEORGE A. SMITH, a citizen of the United States, residing at Baltimore, and State of Maryland, have invented new and useful Improvements in Clothes-Hangers, of which the following is a specification.

This invention relates to clothes hangers.

The object of the invention is to provide a device capable of being extended in order that the clothes from the rear of the hanger may be removed without disturbing those upon the forward part.

Another object is to provide a hanger which may be stamped from sheet metal and put together without the use of bolts or rivets or other auxiliary fastening devices.

With the above objects in view the invention consists of a supporting member having a longitudinal slot therein, a sliding member supported thereby, wheels carried by the said sliding member and a rack carried by the said member for supporting the clothes.

In the drawings:

Figure 1 is a side elevation of the improved clothes rack;

Fig. 2 is a bottom plan view of the same;

Fig. 3 is a section on the line 3-3 of Fig. 1;

Fig. 4 is a section on the line 4-4 of Fig. 1;

Fig. 5 is a section on the line 5-5 of Fig. 1; and

Fig. 6 is an enlarged detail of the portion of the axle and one of the wheels illustrating the manner of securing the wheels to the axle.

In the drawings like characters of reference designate corresponding parts.

The hanger comprises a supporting member 1 formed with the side flanges 2, by means of which the said member is secured in position. This member is preferably formed of sheet metal and is stamped to provide a depending longitudinal portion 3, within which is formed a longitudinal slot 4. The edges of this slot are turned inward as shown at 5 and 6, to provide a smooth surface upon which an axle 7 is adapted to roll. The axle 7 extends through the slot 4 and supports one end of a sliding member 8 formed in the shape of an elongated U. The axle also supports a hanger

9, the free ends of this hanger being provided with openings 10 to receive the said axle. A rack 11 preferably composed of heavy wire has one of its ends secured within the hanger 9 as shown at 12, the opposite end of the rack being secured to the end of the sliding member 8 as shown at 13. This end of the sliding member is supported upon the member 1 by means of a supporting and guiding loop 14 formed from a struck up portion of the member 1. The outer ends of the axle 7 are tapered to receive wheels 15. These wheels are preferably stamped from sheet metal and are provided with an opening 16 to receive the ends of the shaft. They are secured upon the shaft by drawing their central portion into the form of a hollow truncated cone, and driving them in position. By this means it is not necessary to use any other fastening method.

In its normal position the rack is supported upon its inner end by the axle resting upon the edge of the slot, and at its outer end by the supporting loop 14, the wheels 15 being out of engagement with the surface of the supporting member 1. When the rack is pulled outward the weight of the free end causes the inner end to lift, and the wheels 15 to engage the under surface of the member 1. This construction provides for an easy movement of the rack, the parts of the hanger all having a loose fit so that they will not jam.

From the foregoing description, when taken in connection with the accompanying drawings, it will be seen that the invention provides a cheap and attractive hanger for use within a closet, or other restricted space, which permits ready access to the clothes hung in the rear without disturbing those upon the forward end.

Having thus described my invention, I claim:

1. A hanger comprising a supporting member formed with a longitudinal slot, an axle movable along said slot, wheels carried by said axle upon each side of said slot, a sliding member supported at one end upon said axle and means whereby the axle may be elevated to cause the wheels to engage said supporting member.

2. A hanger comprising a supporting member formed with a longitudinal slot, a supporting loop located at one end of said

member, a sliding member movable in said loop, an axle movable along said slot, wheels carried by said axle, a hanger supported by the axle and a rack having one end secured to the hanger and the other end secured to the end of the sliding member, the parts being so arranged as to cause the

axle to be raised from contact with the lower edge of the slot and the engagement of the wheels with the supporting member 10 when the device is in its extended position.

In testimony whereof I affix my signature,

GEORGE A. SMITH.
